[57] CLAIM

The ornamental design for a settee frame or the like, as shown and described.

DESCRIPTION

FIG. 1 is a front elevational view of the settee frame or the like showing my new design;

FIG. 2 is a top plan view thereof, the bottom being substantially plain and unornamented;

FIG. 3 is a rear elevational view thereof; and

FIG. 4 is an end elevational view thereof, the opposite end being substantially a mirror image of that shown.

FIG. 2

FIG. 1

FIG. 4t

FIG. 3
